CLAIM

The ornamental design for a centrifugal pump, as shown and described.

DESCRIPTION

FIG. 1 is a rear perspective view of my centrifugal pump;

FIG. 2 is a rear view thereof;

FIG. 3 is a front view thereof;

FIG. 4 is a top view thereof;

FIG. 5 is a bottom view thereof;

FIG. 6 is a right side view thereof;

FIG. 7 is a left side view thereof; and,

FIG. 8 is a front perspective view thereof.

The broken lines shown in the drawings illustrate portions of my centrifugal pump that form no part of the claimed design.

1 Claim, 8 Drawing Sheets
